A. S. WHEELBARGER

CABINET FOR A REGISTER

Filed Aug. 9, 1928

INVENTOR.
ALBERT S. WHEELBARGER.

by

Hastings W. Baker
his ATTORNEY.

UNITED STATES PATENT OFFICE.

ALBERT S. WHEELBARGER, OF DAYTON, OHIO, ASSIGNOR TO OHMER FARE REGISTER COMPANY, OF DAYTON, OHIO.

DESIGN FOR A CABINET FOR A REGISTER.

Application filed August 9, 1928. Serial No. 27,759. Term of patent 14 years.

To all whom it may concern:

Be it known that I, ALBERT S. WHEELBARGER, a citizen of the United States, residing at Dayton, in the county of Montgomery and State of Ohio, have invented a new, original, and ornamental Design for a Cabinet for a Register, of which the following is a specification, reference being had to the accompanying drawing, forming a part thereof.

The figure is a perspective view of a cabinet for a register showing my new design.

I claim—

The ornamental design for a cabinet for a register as shown.

ALBERT S. WHEELBARGER.
